UNITED STATES PATENT OFFICE

170,541

GAME BOARD

Ralph F. Miles, Pasadena, Calif.

Application September 11, 1952, Serial No. 21,412

Term of patent 3½ years

(Cl. D34—5)

To all whom it may concern:

Be it known that I, Ralph F. Miles, a citizen of the United States, residing at Pasadena, in the county of Los Angeles and State of California, have invented a new, original, and ornamental Design for a Game Board, of which the following is a specification, reference being had to the accompanying drawing, forming part thereof.

The single drawing figure is a plan view of a game board, showing my new design.

The motif of the design appearing in the left upper quarter is repeated in the other three quarters, symmetrically with respect to the center of the game board.

The game board is of a conventional thickness.

I claim:

The ornamental design for a game board, as shown and described.

RALPH F. MILES.
